UNITED STATES PATENT OFFICE.

CLARENCE D. PLATT, OF BRIDGEPORT, CONNECTICUT.

ELECTRIC SWITCH.

1,333,185.

Specification of Letters Patent. Patented Mar. 9, 1920.

Application filed May 3, 1919. Serial No. 294,455.

To all whom it may concern:

Be it known that I, CLARENCE D. PLATT, a citizen of the United States of America, residing at Bridgeport, Conn., have invented new and useful Electric Switches, of which the following is a specification.

The present invention relates particularly to the mounting of switch handles, and the objects of the invention are to provide a simple and practical form of mounting which can be easily assembled and which when assembled will secure the switch handle in proper position.

This mounting consists of a bushing which is journaled in the support and is provided with a flange or shoulder limiting the movement of the bushing in one direction, said bushing receiving the handle shaft, and a cross pin or other device being provided for securing the shaft in the bushing and for limiting the movement of the bushing and shaft in the opposite direction.

This construction will be better understood from a consideration of the accompanying drawing wherein I have illustrated the invention embodied in a practical and preferred form.

In said drawing:

Figure 1 is a plan view of an inclosed switch having the invention incorporated therein, the switch box being shown in open position.

Fig. 2, is a cross sectional view of the same taken substantially on the plane of the line 35 2-2 of Fig. 1.

Fig. 3, is a broken perspective view illustrating assemblage of the parts.

The handle 5 for the switch illustrated is in the form of a rod or shaft having a cranked portion 6 connected with the movable switch element 7 by a link 8.

This operating shaft is journaled, in the present disclosure, in the opposite side walls of the box 9 which incloses the switch parts, said box having for the purpose bearing openings 10 and 11 in its opposite side walls.

12 designates the supporting bushing journaled in the bearing opening 11 and provided with an outstanding annular flange 13 at its outer end engaging the outer face of the wall to limit the inward movement of the bushing. One end of the operating shaft is engaged and supported in this bushing, said shaft being secured therein, in the present illustration, by a pin or key 14 passed

through the bushing and shaft at the inner face of the supporting wall. This pin thus serves both to secure the shaft in the bushing and to limit the outward movement of the bushing and supported shaft in the bearing 60 opening.

In the construction shown, the parts are assembled by inserting the bushing in the bearing opening 11, with the flange at the outside of the box and by inserting the shaft 65 through the bearing opening 10 in the opposite wall of the box into engagement in its seat in the bushing, the securing pin being then passed through the bushing and shaft to secure the parts in this relation. The 70 flange of the bushing then limits the longitudinal movement of the shaft in one direction and the securing pin limits the longitudinal movement of the shaft in the opposite direction, and at the same time, the parts 75 may be quickly disassembled upon withdrawing the securing pin. In addition to providing a secure and easily assembled mounting for the shaft, the invention provides also a neat finish for the journal of the 80 shaft.

I claim:

1. In a switch box, the combination of a supporting wall, a bushing extending through said wall and provided with a shoulder at one end engaging one side of the supporting wall to limit movement of the same in one direction, a shaft engaged in said bushing and means at the opposite side of the supporting wall for securing the shaft 90 in the bushing and engaging said opposite side of the wall to limit movement of the bushing and the shaft engaged therein in the opposite direction.

2. In a device of the character described, 95 the combination of a supporting wall, a bushing extending through said wall and provided with a shoulder at one end engaging one side of the supporting wall to limit movement of the same in one direction, a shaft engaged in said bushing and a pin at the opposite side of the supporting wall extending through the bushing and into the shaft engaged therein to thereby secure said shaft in the bushing and to provide a stop for engagement with said opposite side of the supporting wall.

3. The combination with a switch box provided with bearing openings in its opposite walls, of a bushing engaged in one of 110

2

said bearing openings and provided with a flange forming a stop shoulder for limiting the movement of the bushing in one direction, a switch operating shaft engaged in 5 said bushing and having its opposite end portion engaged in the bearing opening in the opposite wall of the box and means for securing said shaft in the bushing and forming a stop shoulder to limit movement in the 10 opposite direction of the bushing and the shaft secured therein.

4. The combination with a switch box provided with bearing openings in its opposite walls, of a bushing seated in one of said 15 bearing openings and provided with a flange forming a stop bearing against the outer side of the wall to limit inward movement of the bushing, a switch operating shaft engaged in said bushing at one end 20 and bearing at its opposite end in the bearing opening in the opposite wall of the box and means for securing the shaft in the bushing disposed at the inside of the box and forming an abutment limiting outward 25 shifting movement of the bushing and the shaft engaged therein.

5. The combination with a switch box provided with a bearing opening in one wall thereof, of a bushing journaled in said 30 bearing opening and provided with an outstanding flange limiting movement of the bushing in one direction, a switch operating member engaged in said bushing and means for securing said member in said bushing, 35 said means forming a stop limiting move-

ment in the opposite direction of the bushing and operating member secured therein.

6. The combination with a switch box provided with bearing openings in the opposite walls thereof, of a bushing seated in 40 one of said bearing openings and having a flange engaging one side of the box wall, a switch operating handle having a shaft portion passed through the bearing opening in the opposite wall and into engagement 45 in said bushing, said bushing and shaft having complementary openings therein at the side of the box wall opposite that engaged by the flange on the bushing and a securing pin passed through the said complementary 50 openings to fasten the handle shaft to the bushing and to limit movement of the same toward the box wall.

7. An inclosed switch comprising the combination of a box having bearing openings 55 in its opposite walls, switch mechanism mounted in the box, an operating shaft having an offset crank portion connected to the switch mechanism, one end of said shaft being rotatably supported in one of the bearing openings, a sleeve surrounding the opposite end of said shaft in the opposite opening, means on the exterior of said sleeve for preventing inward movement of the sleeve, and means on the interior of the box 60 for connecting said sleeve to said shaft, and preventing outward movement of said sleeve, whereby the shaft is prevented from longitudinal movement in either direction.

C. D. PLATT.
